UNITED STATES PATENT OFFICE

112,656

DESIGN FOR A WINDOWED CANISTER

Richard S. Hirschland, Harrison, N. Y., assignor
to Geo. V. Clark Co., Inc., Long Island City,
N. Y., a corporation of New York

Application September 21, 1938, Serial No. 80,027

Term of patent 7 years

To all whom it may concern:

Be it known that I, Richard S. Hirschland, a citizen of the United States and a resident of Harrison, in the county of Westchester of the State of New York, have invented a new, original, and ornamental Design for a Windowed Canister, of which the following is a specification, reference being had to the accompanying drawing, forming part thereof.

In the drawing, the figure is a perspective

view of the canister, showing my design, the opposite side of the canister being plain. The window of the canister is of transparent material. The dominant features of the design are shown in full lines.

I claim:

The ornamental design for a windowed canister, substantially as shown and described.

RICHARD S. HIRSCHLAND.
